US0D1101255S

(12) **United States Design Patent** (10) **Patent No.:** **US D1,101,255 S**
(45) **Date of Patent:** **** Nov. 4, 2025**

(54) **VAPING CARTRIDGE**

(71) Applicant: **Next Level Ventures LLC**, Seattle, WA (US)

(72) Inventor: **Alex Gordon**, Irvine, CA (US)

(73) Assignee: **Next Level Ventures LLC**, Seattle, WA (US)

(**) Term: **15 Years**

(21) Appl. No.: **29/902,522**

(22) Filed: **Sep. 13, 2023**

(51) LOC (15) Cl. **27-02**

(52) U.S. Cl.

USPC **D27/162**

(58) **Field of Classification Search**

USPC ..... D27/162, 100, 101, 163–165, 170, 172, D27/174, 183, 185–194; D23/366; D24/110, 110.5; D13/103, 107 CPC A24F 47/002; A24F 47/006; A24F 47/008; A61M 15/00; A61M 15/06

See application file for complete search history.

(57) **CLAIM**

The ornamental design for a vaping cartridge, as shown and described.

DESCRIPTION

FIG. 1 is a perspective view of a new design for a vaping cartridge.

FIG. 2 is a front view of FIG. 1.

FIG. 3 is a back view of FIG. 1.

FIG. 4 is a left side view of FIG. 1.

FIG. 5 is a right view of FIG. 1.

FIG. 6 is a top view of FIG. 1; and,

FIG. 7 is a bottom view of FIG. 1.

The broken lines in the drawings depict portions of the vaping cartridge that form no part of the claimed design.
